Primary Examiner — Bao-Yen T Nguyen*Assistant Examiner* — Christopher John Suarez La Rosa(74) Attorney, Agent, or Firm — Stites & Harbison, PLLC; David W. Nagle, Jr.(57) CLAIM

The ornamental design for a picnic basket as shown and described.

DESCRIPTION

FIG. 1 is a front view of a picnic basket incorporating the design of the present invention;

FIG. 2 is another front view of the picnic basket of FIG. 1, shown in an alternate configuration;

FIG. 3 is a rear view of the picnic basket of FIG. 1;

FIG. 4 is a left side view of the picnic basket of FIG. 1;

FIG. 5 is a right side view of the picnic basket of FIG. 1;

FIG. 6 is a top view of the picnic basket of FIG. 1; and,

FIG. 7 is a bottom view of the picnic basket of FIG. 1.

The dash-dash broken lines showing a strap and hooks depict portions of the picnic basket that form no part of the claimed design.

1 Claim, 7 Drawing Sheets(56)
